DESIGN FOR A DOLL

Agop M. Agopoff and Ralph A. Freundlich, New York, N. Y., assignors to Freundlich Novelty Corporation, New York, N. Y., a corporation of New York

Application December 8, 1941, Serial No. 104,535

Term of patent 7 years

To all whom it may concern:

Be it known that we, Agop M. Agopoff and Ralph A. Freundlich, both citizens of the United States and residing at 256 West 55th Street, and 27 West 86th Street, New York, in the county and State of New York, respectively, have invented a new, original, and ornamental Design for a Doll, of which the following is a specification, reference being had to the accompanying drawing, forming part thereof.

In the accompanying drawing, Fig. 1 is a rear elevational view of a doll showing our new design; Fig. 2 is a side elevational view thereof; Fig. 3 is a front elevational view thereof; and Fig. 4 is a three-quarter side perspective view thereof.

We claim:

The ornamental design for a doll, as shown.

AGOP M. AGOPOFF.
